DESIGN.

—o—
J. L. FOLSOM.

CARPET.

No. 18,134.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,134, dated March 6, 1888.

Application filed January 26, 1888. Serial No. 262,057. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is a composite design consisting of an assemblage of flower, leaf, and geometrical forms of varied size and character, arranged in a more or less irregular manner. The flower

forms are generally circular or oval in form. 20 At one part of the design is cellular-like ornamentation. A checker or lattice work is shown in different places, having small ornamental figures in the blocks or squares. Here and there are small portions of border-work of 25 varying character. Scroll forms also occur among the other figures. At the middle of the design is a line-work ornamentation producing a watered effect.

What I claim as new, and desire to secure 30 by Letters Patent, is—

The design for carpets, consisting of the de-sign substantially as shown.

JAS. L. FOLSOM.
